Primary Examiner — Robert M Spear*Assistant Examiner* — Darcey E Heflin(74) *Attorney, Agent, or Firm* — Thompson Coburn LLP; Alan H. Norman(57) **CLAIM**

The ornamental design for a closure, as shown and described.

DESCRIPTION

FIG. 1 is a perspective view of a closure showing our new design with the closure in an open position;

FIG. 2 is a top view thereof;

FIG. 3 is a right view thereof;

FIG. 4 is a left side view thereof;

FIG. 5 is a rear side view thereof;

FIG. 6 is a front plan view thereof; and,

FIG. 7 is a perspective view thereof with the closure in a closed position.

The bottom and interior surfaces of the closure are non-ornamental and does not form a part of our new design.
